COIN-OPERATED WEIGHING AND
DISPENSING DEVICE

Kurt B. Nelson, Pittsburgh, Pa.

Application September 30, 1936, Serial No. 103,301

2 Claims. (Cl. 249—2)

This invention relates to a coin-operated device for dispensing fluid and, in particular, to a device for accurately measuring the material before dispensing it. The device has a wide range 5 of uses which will become apparent as the detailed description thereof proceeds.

Numerous forms of liquid dispensers operated by coins have been known heretofore, but none of them, so far as I am aware, approach the 10 degree of accuracy in measurement which is required in certain applications. It is an object of my invention, therefore, to improve upon devices of this character which have been known previously by providing a dispenser which is 15 capable of drawing liquid from an original container and measuring it with extreme accuracy before dispensing it. Other features of novelty characterizing my invention relate to the handling of the coins used to operate the measuring 20 mechanism.

In accordance with the invention, I provide a dispensing receptacle and a siphon adapted to draw liquid from a supply container located above the receptacle. A measuring receptacle is 25 movably mounted below the dispensing receptacle. Valve mechanism controlled by movement of the measuring receptacle admits fluid from the dispensing receptacle to the measuring receptacle. Such movement of the measuring receptacle is effected by coin-operated mechanism. 30 For a complete understanding of the invention, reference is made to the accompanying drawings illustrating a preferred embodiment. In the drawings,

Fig. 1 is an elevation showing the apparatus mounted on a panel;

Fig. 2 is a side elevation showing the panel in section;

Fig. 3 is a front elevation of the panel itself;

Fig. 4 is an enlarged view of a detail;

Fig. 5 is a sectional view taken along the line V—V of Fig. 1;

Fig. 6 is a sectional view taken along the line VI—VI of Fig. 1; and

Fig. 7 is a sectional view taken along the line VII—VII of Fig. 1.

Referring now in detail to the drawings, the apparatus of my invention is adapted for mounting on a panel 10 having a coin slot 11, a recess 12 for the consumer's receptacle, a window 13 behind which a supply container 14 is disposed so that the label on the container may be read through the window, and a slug-detecting window 15.

Fig. 8 shows the apparatus mounted on the back of the

panel 10 comprises a shelf bracket 16 for supporting the supply container 14, a dispensing receptacle 17, a siphon 18 connecting the receptacle and the container, a measuring receptacle 19, and other elements which will be described in detail 5 hereinafter.

The siphon 18 comprises a limb 20 adapted to be inserted in the container 14 and a limb 21 extending through a two-hole stopper 22 in the receptacle 17. The limb 20 may be inserted 10 through a one-hole stopper disposed in the mouth of the container 14, but this stopper must be vented to the atmosphere. The limbs 20 and 21 are connected by a swivel 23 comprising a cork sleeve 24 secured in a supporting collar 25 and 15 bored to receive the angularly disposed ends of the limbs. A layer of wax 26 is poured into the bore through the cork sleeve before the limbs of the siphon are inserted. This facilitates rotation of the limbs in the sleeve and the maintenance of an air-tight seal between the sleeve and the limbs.

To insert the limb 20 in the container 14, the limb is swung to the position shown in dotted lines in Fig. 2, and the container moved so that 25 the limb reaches almost to the bottom thereof, whereupon the container and limb may be swung together toward the shelf bracket 16.

A suction pump 27, preferably of the bulb type, has a connection 28 to the interior of the receptacle 17, extending through the stopper 22.

The receptacle 17 is supported on the panel by bracket rings 29 secured thereto, and has a discharge port or hole 30 in its bottom. A valve 31, preferably a glass ball, is ground to fit accurately in the opening 30 to seal it against discharge of fluid. The valve 31 is carried on a valve stem 32 depending below the receptacle 17.

The measuring receptacle 19 is seated in a holding ring 33 carried at one end of a lever 34 40 pivoted on a shaft 35. The shaft 35 is journaled in bearings carried on a bracket 36 secured to the panel. A stud 37 is secured to the lever 34 extending in line with the latter, as shown in Fig. 1. A nut 38 threaded on the stud 37 carries a loop 39 from which a counterweight 40 is suspended.

By reason of the pivotal mounting of the lever 34, the counterweight 40, when properly adjusted on the stem 37, tends to cause the measuring receptacle 19 to move toward the dispensing receptacle 17. The measuring receptacle 19 has a bottom discharge opening 41. A valve 42 similar to the valve 31 is carried on the stem 32 for closing the opening 41 when the receptacle 19 is raised. Such movement of the receptacle is also 55

effective to open the valve 31 after closing the valve 42.

A shaft 43 is journaled in bearings 44 extending upwardly from the bracket 36 above the lever 34. A toggle linkage 45 has a member 46 secured to the shaft 43, and members 47 pivoted to the member 46 and to the lever 34 as best shown in Figs. 4 and 5. When the linkage is extended, as shown in Figs. 1, 4 and 5, elevation of the receptacle 19 by the counterweight 40 is prevented. The linkage thus constitutes a mechanical lock-out which must be tripped before the valves 31 and 42 can be actuated by movement of the receptacle 19 to admit fluid to the latter. I provide coin-operated mechanism, which I shall now describe in detail, for collapsing the linkage 45.

A coin chute 48 comprises a slug throwout section 49, a tilting arm 50 and cooperating guide 51, and a slug-detector section 52. The slug throwout section 49 is disposed at an angle to the vertical and provided with a throwout opening 53. The arm 50 has an open ended pocket 54 for receiving a coin from the throwout section 49. The arm 50 is tiltable on a shaft 55 journaled in bearings 56 secured to the panel 10. A link 57 is pivoted to the arm 50 beyond the shaft 55. The other end of the link 57 is pivoted to a crank arm 58 rigid with the shaft 43. The arm 58 has a counterweight providing a sufficient pull on the link 57 to hold the parts in the illustrated position until a coin reaches the pocket 54.

When a coin deposited in the slot 11 traverses the section 49 of the chute and drops into the pocket 54, the impact is sufficient to swing the latter downward into the upper end of the slug-detector section 52, as shown in dotted lines in Fig. 2. When the arm 50 reaches this position the coin escapes therefrom and rolls on down the section 52. The coin is held in the pocket 54 as the arm swings down by the guide 51.

The downward swing of the arm 50 raises the crank arm 58 and turns the shaft 43 to collapse the linkage 45. This permits the counterweight to raise the receptacle 19, closing valve 42 and opening valve 31. An additional counterweight 59 is carried on a flexible arm 60 extending upwardly from the lever 34. This counterweight can be adjusted by bending the arm 60. This adjustment, together with that of the counterweight 40, permits the device to be controlled accurately for measuring precisely the desired amount of fluid.

The weight of the fluid flowing into the receptacle 19 from the receptacle 17 overbalances the counterweights 40 and 59 when a predetermined amount of fluid has been admitted to the receptacle 19. The latter thereupon drops, closing valve 31 and opening valve 42. The fluid in the receptacle 19 then runs out into a funnel 61, and thence into a consumer's receptacle 62 in the recess 12. The restoration of the lever 34 to the illustrated position extends the linkage 45, and with the aid of the counterweight on the arm 58 restores the arm 50 to its normal position.

Coins running down the slug-detector section 52 land on a coin holder 63. This is preferably a rod having longitudinal grooves, mounted for rotation about a longitudinal axis. The rod may conveniently be mounted on the shaft 64 journaled in suitable bearings carried on the panel 10. The coin holder 63 lies in an open-bottomed pocket 65 at the end of the section 52 and above a chute 66 leading to a coin box 67. The pocket 65 is just behind the slug-detector window 15.

The shaft 64 has a square nut 67 secured there-

to. A spring strap 68 carried by the link 57 has sliding engagement with the nut 67, and a bend 69 in the strap is effective to notch the nut 67 around a quarter turn on each reciprocation of the link 57. The passage of successive coins through the chute 48 thus causes the holder 63 to turn and dump the coin previously deposited thereon into the chute 66. By this construction, each coin deposited remains in view behind the window 15 until the succeeding operation of the 10 machine. This facilitates the detection of slugs, and acts as a deterrent to the use thereof.

The operation of the device, while it will probably be apparent from what has already been said, will be briefly reviewed here. The panel 10 15 is preferably hinged to a cabinet suitable for wall mounting. The container 14 may then be easily placed in position by swinging the panel out from the cabinet and tilting the limb 20 of the siphon 18. If the device is being placed in operation for the first time, it will be necessary to operate the bulb pump 27 to draw sufficient fluid from the container 14 to fill the receptacle 17. If an empty container 14 is being replaced, the receptacle 17 will probably be full of liquid, because 25 customers will not use the device when they observe through the window 13 that the supply in the container 14 is exhausted; although as a matter of fact, the device will dispense the contents of the receptacle 17 even after the supply in the 30 container 14 has all been drawn over into the receptacle. It will be understood that the valves must be in the illustrated position before operating the pump 27. The device is ready for operation as soon as the level of the fluid in the 35 receptacle 17 rises above the lower end of the limb 20.

A coin deposited in the slot 11, as already described, causes the arm 50 to swing. This rotates the shaft 43 and trips the lockout linkage 45. 40 The counterweight 40 raises the receptacle or cup 19, closing the valve 42 and opening the valve 31, whereupon fluid flows into the cup. When sufficient fluid has been delivered to the cup, the weight thereof overbalances the counterweight 45 40 and the other counterweights, and restores the cup 19, the linkage 45 and the arm 50 to their illustrated positions, closing the valve 31 and opening the valve 42. The fluid in the cup 19 then runs out into the funnel 61 and the consumer's receptacle 62 which must, of course, be placed under the funnel tip before the coin is deposited.

The coin rolls down the slug-detector section 52 onto the coin holder 63, the reciprocation of 55 the link 57 having rotated the holder to discharge the coin previously deposited.

It will be apparent from the foregoing description that the invention provides a highly useful and efficient mechanism for dispensing fluids. 60 The construction is simple and inexpensive, yet sturdy and easy to maintain. Servicing the device is also a relatively simple matter. Its accuracy of measurement has already been mentioned. A particular advantage is that the device dispenses from the original container. This is a legal requirement for alcoholic beverages, in some states. Although controlled by weights and balances, the device operates very rapidly. The control valves require relatively little effort for 70 their operation, yet can be made to seat very accurately, thus preventing leakage. The amount of fluid dispensed can readily be controlled by adjusting the counterweights.

The window 13 makes it possible for the cus- 75

tomer to see that the fluid is being dispensed from the original container, and to choose his brand by the label on the container 14.

Although I have illustrated and described herein but a preferred embodiment of the invention, it will be understood that changes in the construction disclosed may be made without departing from the spirit of the invention or the scope of the appended claims.

10 I claim:

1. A dispenser comprising a measure mounted on a pivoted, counterweighted lever, and fluid supply means including means operable on tilting of the lever to admit fluid to said measure, the weight of the fluid in the measure tending to restore the lever to its original position, and a pair of toggle links pivoted to said lever and a fixed bearing respectively, said links being pivoted

together, means normally holding said links in alinement thereby preventing tilting of the lever, and coin-operated means effective to collapse said links to permit tilting of said lever.

2. A dispenser comprising a measure mounted on a pivoted, counterweighted lever, and fluid supply means including means operable on tilting of the lever to admit fluid to said measure, the weight of the fluid in the measure tending to restore the lever to its original position, and a pair of toggle links pivoted to said lever and a fixed bearing respectively, said links being pivoted together, means normally holding said links in alinement thereby preventing tilting of the lever, and means under the control of a user, effective to collapse said links to permit tilting of said lever.

KURT B. NELSON.
